IRONING MACHINE

Harold L. Hart, River Forest, Ill., assignor to
Electric Household Utilities Corporation, Chi-
cago, Ill., a corporation of Illinois

Application April 2, 1932, Serial No. 602,764

9 Claims. (Cl. 68—9)

This invention relates to improvements in ironing machines and its purpose is to provide a new type of ironing machine in which the ironing elements have relative reciprocatory movements similar to the movement of a flatiron over an ironing board in the operation of ironing manually. Heretofore, power-driven ironing machines have usually been of that type in which a rotatable power-driven roll cooperates with a relatively movable shoe but such machines, while successful for most classes of work, are not capable of being built in very small sizes and are not well adapted for some classes of ironing. Pressing machines have heretofore been provided wherein two flat plates have been mounted to compress between them the article to be pressed but these flat plates have had no relative reciprocatory movement parallel to their contacting surfaces and have been suited only for the pressing of men's suits and the like.

The principal object of the present invention is to provide a new form of machine in which two ironing elements, having flat parallel ironing surfaces, are adapted to have relative reciprocatory movement parallel to these surfaces so that the machine retains the advantages of manual operations with the flatiron while obtaining the additional advantages of power operation and simplicity of construction and operation, as compared with other power-driven machines. A further object of the invention is to provide an ironing machine comprising a pair of relatively movable plates extending horizontally and having means for reciprocating one of said plates parallel to the surface of the other. A further object of the invention is to provide an ironing machine comprising two relatively movable ironing elements in the form of two flat plates in combination with means for effecting relative reciprocation of said plates parallel to the planes of their ironing surfaces and means for separating said plates to permit the insertion of clothes therebetween. Still another object is to provide an ironing machine of the type referred to in which the ironing plates may be separated without discontinuing the reciprocatory motion of one of said plates. A further object of the invention is to provide a simple and efficient form of driving mechanism for effecting relative reciprocatory movement of two ironing elements. Other objects relate to various features of construction and arrangement which will appear more fully hereinafter.

The nature of the invention will be understood

from the following specification taken with the accompanying drawings, in which one embodiment is illustrated. In the drawings,

Fig. 1 shows a top plan view of the improved ironing machine with a portion thereof broken away;

Fig. 2 shows a side elevation of the ironing machine illustrated in Fig. 1, with a part thereof shown in vertical section;

Fig. 3 shows a detail section taken on the line 10—3 of Fig. 1;

Fig. 4 shows a transverse vertical section taken on the line 4—4 of Fig. 2;

Fig. 5 shows an enlarged horizontal detail section taken on the line 5—5 of Fig. 2; 15

Fig. 6 shows a transverse vertical section taken on the line 6—6 of Fig. 5; and

Fig. 7 shows a top plan view of the clutch member by which the separation of the ironing elements is controlled. 20

As illustrated in the drawings, the invention is embodied in an ironing machine comprising a base or casing 10 which is adapted to rest upon a table or the like and which comprises an enlarged front portion 10^a of rectangular outline 25 connected with a central rearward extension 10^b. The front portion 10^a of this casing has a flat horizontal upper surface formed by its top wall 10^c above which are located the two relatively movable ironing elements 11 and 12 which are 30 constructed in the form of horizontal plates of rectangular form having oppositely disposed flat surfaces adapted to receive between them the clothes to be ironed. The lower ironing element 11 comprises an inner metal plate 11^a having 35 mounted thereon and secured thereto a covering 11^b of suitable fabric adapted to engage the clothes to be ironed. The other plate 12 is of hollow construction and has mounted therein an electric heating element provided with terminals 40 13 which are connected in an electric circuit, not illustrated, so that the plate 12 may be heated during the ironing operation. The plate 11^a of the lower ironing element has secured thereto four vertical supporting posts 14 which are 45 adapted to slide in the tubular bores 15 formed in the top wall of the casing. The casing 10 is provided with bosses 10^d beneath these apertures 15, forming recesses in which are mounted coil springs 16 to engage the reduced lower extremities 14^a of the posts 14. The ironing element 11 is thus resiliently mounted and is adapted to yield under pressure applied thereto through the upper ironing element 12. 50

For the purpose of moving the heated ironing 55

element 12, it is connected to an arm or lever 18 by means of a pin 19 which passes through the extremity of this lever and through a pair of ears 12^a extending upwardly from a boss 12^b formed 5 on the central part of the upper side of the plate 12. The lever 18 is turned downwardly at the end thereof opposite the pivot pin 19 and extends between the two bars 21^a of a lever 21 on which it is pivotally supported by a pin 20. These bars 10 extend downwardly through slots 10^c formed in the upper wall 10^c of the rearward extension of 15 the casing. A hub 22 is secured to this top wall 10^c between the bars 21^a of the lever 21, and these bars are pivoted on this hub by means of a transverse pin or rivet 23. A filler block 24 is mounted between the lower ends of the bars 21^a and a pin 25, passing through this block and the ends of the bars, serves to establish a pivotal connection between the lever 21 and the head 26^a 20 of a connecting rod 26 which is actuated, in the manner hereinafter described, to actuate the lever 18 and thereby impart a reciprocating motion to the plate 12.

The arm or lever 18 has a short arm 18^a extending from the pivot pin 20 toward the front portion 10^a of the casing and this short arm projects between two bars 21^a of a link 27 which passes downwardly through the slot 10^c in the top wall of the casing. The link 27 is pivotally 30 connected at its upper end to the arm 18^a of the lever by means of a pin 28 and at its lower end it is pivotally connected by a pin 29 to the two side plates 30^a of a bell crank lever 30. These plates 30^a extend on opposite sides of an ear 31 which is 35 formed on the under side of the top wall 10^c of the rearward extension of the casing and are pivotally connected thereto by a pin 32. The lower extremities of these triangular plates 30^a are pivotally connected by another pin 33 to the head 34^a of another connecting rod 34 which is adapted to be actuated in the manner hereinafter described to effect movement of the ironing element or plate 12 toward and from the lower ironing element 11. A sheet metal housing 17 is 40 mounted on the top of the wall 10^c of the rear extension of the casing to enclose the rear extremity of the lever 18 and the upper parts of the members 21 and 27, thus preventing engagement of the clothes with the operating mechanism. 45 This housing 17 has an opening in its upper wall through which the lever 18 extends.

The two connecting rods 26 and 34 are actuated by a common shaft 35 which is journaled in bearings 36, carried by one end wall of the casing 50 and by a parallel division wall 10^c which is spaced inwardly from the other end wall. The shaft 35 is adapted to be driven through a train of gearing by an electric motor 36 which is secured to the last-named end wall of the casing 55 with its shaft 37 journaled in a bearing 38 carried by this end wall. A pinion 39, secured upon the end of the shaft 37 and journaled upon the reduced extremity 35^a of the shaft 35, is arranged to mesh with a gear 40 secured upon a counter-shaft 41 having bearings 42 carried by the division wall 10^c and the adjacent end wall of the casing. This shaft 41 also has secured thereon a pinion 43 which meshes with a gear 44 secured on the shaft 35 so that when the motor 36 is in 60 operation, the shaft 35 is continuously driven at a reduced speed as compared with the speed of the motor shaft. The shaft 35 has an eccentric 45 secured thereon by a pin 46 and this eccentric is provided with an annular groove 45^a engaged 70 by an eccentric strap 46 provided with projecting

ears 46^a which are secured together by a screw 47. The eccentric strap 46 is provided with a head 46^b having a threaded socket which is engaged by the threaded extremity of the connecting rod 26 so that the effective length of the connecting rod may be varied. The parts are held in adjusted position by a lock nut 48. When the shaft 35 rotates, the eccentric 45 is continuously driven to actuate the lever 21 through the connecting rod 26 and thereby oscillate the lever 18 about the pin 28 to cause a reciprocating motion of the ironing plate 12 over the lower ironing element or table 11.

The other connecting rod 34 is adapted to be actuated by another eccentric 50 which is rotatably mounted upon the shaft 35 and spaced from the eccentric 45 by a washer 51. The eccentric 50 is provided with an annular groove 50^a engaged by an eccentric strap 52 having projecting ears 52^a which are secured together by a screw 53. This eccentric strap is provided with a projecting head 52^b having a threaded socket which is engaged by the threaded extremity of the connecting rod 34 which is held in adjusted position by a lock nut 54. The eccentric 50 is provided in its lateral side with a pair of cylindrical recesses 50^b which extend parallel to the axis of the shaft 35 and are engaged by pins 55 projecting from the side of a clutch member 56. Coil springs 57 which are mounted in the recesses 50^b engage the ends of the pins 55 and thus force the clutch member 56 away from the eccentric 50, the clutch member being rotatably and slidably mounted upon the shaft 35. The springs 57 also serve to maintain the eccentric 50 in position against the washer 51. The clutch member 56 comprises an annular gear 56^a having teeth which are adapted to mesh with the internal annular gear teeth 58^a of a complementary clutch member 58 secured upon the shaft 40 by a pin 59. When the teeth of the gear 56^a engage the teeth 58^a of the clutch member 58, a driving connection is established between the shaft 35 and the eccentric 50 through the intermediate clutch member 56 so that the connecting rod 34 is then actuated by the eccentric 50 to rock the bell crank lever 30 and thereby cause the link 27 to move the lever 18 about the pivot pin 20 for the purpose of raising or lowering the ironing plate 12 with respect to the 45 lower plate 11.

The movement of the clutch member 56 for the purpose of controlling the driving connection between the shaft 35 and the eccentric 50 is manually controlled by a finger bar 60 carried 55 at the front of the casing 10 upon a pair of arms 61 which extend through slots in the front wall of the casing and are secured upon a shaft 62 having its ends journaled in bearings carried by one end wall of the casing and the transverse division wall 10^c. The shaft 62 has another arm or lever 63 secured thereon and provided with a roller 63^a which is adapted to engage an annular cam slot 56^b formed in the annular face of the clutch member 56. A coil 65 spring 65 is connected to one of the arms 61 and to the top wall 10^c of the casing, as shown in Fig. 3, so that it normally forces the roller 63^a into engagement with the clutch member 56. The cam slot 56^b is provided with a pair of 70 oppositely disposed portions 56^c which project away from the adjacent eccentric 50 so that when the roller 63^a is in engagement with the slot 56^b, at one of the points 56^c, the clutch member 56 is held in its retracted position, dis- 75

connected from the clutch member 58, thus permitting the shaft 35 to rotate without operating the eccentric 50. When the operator depresses the finger bar 60, the roller 63^a is elevated out of engagement with the cam slot 56^b, thus allowing the springs 57 to force the clutch member 56 into driving engagement with the clutch member 58, whereupon the eccentric 50 is rotated and the shoe or plate 12 is raised or lowered through the operation of the connecting rod 34 in rocking the bell crank lever 30 and thereby tilting the lever 18 about the pivot pin 20. If the finger bar 60 be immediately released, after being thus depressed, the spring 65 will operate to return the roller 63^a into engagement with the clutch member 56 so that it will again drop into engagement with the groove 56^b and thus operate, at the end of a half-revolution of the eccentric 50, to withdraw the clutch member 56 from its driving engagement with the clutch member 58 and thus hold the plate or shoe 12 in either its retracted position or its ironing position, depending upon the direction in which it has just been moved. Assuming that the ironing shoe 25 has just been elevated by its operation, it remains elevated until the operator has inserted the clothes between the members 11 and 12, whereupon the finger bar 60 is again depressed to raise the roller 63^a out of the cam slot 56 and permit the clutch members 56 and 58 to engage each other again. If the finger bar 60 be immediately released, the roller 63^a will again automatically engage the slot 56^b and thus cause the disengagement of the clutch members at the 35 end of another half-revolution when the ironing shoe 12 will have been restored to its ironing position. Of course, if the finger bar 60 be depressed and held in that position for a considerable time, the plate or shoe 12 will continue to be raised and lowered without interruption until the finger bar is released. The parts are so constructed that when the plate or shoe 12 is in its lower ironing position, it engages the clothes on the plate 11 with considerable pressure and 40 the plate 11 is therefore resiliently mounted so that it may yield somewhat under the pressure of the plate 12 and accommodate itself to the thickness of the clothes being ironed. As soon as the plate 12 is lowered, with the clothes in 45 position on the plate 11, the reciprocatory motion of the plate 12, which continues as long as the motor 36 is in operation, begins the ironing movement, and this is continued until the finger bar 60 is again depressed to cause the shoe 12 55 to be elevated.

Although one form of the invention has been shown and described by way of illustration, it will be understood that it may be constructed in various other embodiments within the scope of 60 the appended claims.

I claim:

1. The combination in an ironing machine, of a horizontal ironing plate, a second plate mounted over said first named plate, a single lever connected to and supporting said second named plate, an upwardly extending support pivotally mounted at its intermediate point and having its upper end pivotally connected to and supporting said lever, and reciprocating means connected to 65 the lower end of said support and movable horizontally for effecting a reciprocating motion thereof to cause said second named plate to move back and forth in a horizontal plane over said first named plate.

2. The combination in an ironing machine, of

a casing adapted to rest upon a table, an ironing plate mounted on said casing, an ironing shoe disposed above said plate, a lever having one end pivotally connected to an intermediate part of said shoe, an upwardly extending actuating lever 5 pivotally connected to the opposite end of said first named lever, means for pivotally supporting said actuating lever at an intermediate point, and power driven means connected to the free end of said actuating lever and having a reciprocating motion horizontally for imparting a reciprocating motion in a horizontal plane to said ironing shoe.

3. The combination in an ironing machine, of a pair of cooperating ironing plates having flat ironing surfaces, an arm connected to one of said plates, an operating shaft, a driving motor having a connection for continuously rotating said shaft, means comprising an eccentric driven by said shaft for continuously actuating said arm to reciprocate one of said ironing plates parallel to 20 the surface of the other ironing plate, means comprising another eccentric rotatably mounted on said shaft for actuating said arm to effect relative movement of said plates toward and from each other, a clutch for controlling the driving 25 connection between said last named eccentric and said operating shaft, and manually operated means for controlling the actuation of said clutch.

4. The combination in an ironing machine, of a portable casing adapted to rest upon a table, an ironing element mounted on said casing, a second ironing element positioned above said first named ironing element, an arm connected to said second named ironing element and extending horizontally rearward therefrom, said arm having its rear end turned downwardly, said down-turned portion having a forward projection, a supporting lever pivotally connected to said down-turned portion of said arm, another member pivotally connected to said forward extension of said arm, and means for actuating said supporting lever to rock said arm about said last named member and thereby reciprocate said second named ironing element over the surface of said first named ironing element.

5. The combination in an ironing machine, of a portable casing adapted to rest upon a table, an ironing element mounted on said casing, a second ironing element positioned above said first named ironing element, an arm connected to said second named ironing element and extending horizontally rearward therefrom, said arm having its rear end turned downwardly, said down-turned portion having a forward projection, a supporting lever pivotally connected to said down-turned portion of said arm, another member pivotally connected to said forward extension of said arm, an operating shaft in said casing, an eccentric mounted on said shaft, and means connecting said eccentric with said supporting lever for rocking said supporting lever about its pivot and thereby actuating said arm about said member.

6. The combination in an ironing machine, of a portable casing adapted to rest upon a table, an ironing element mounted on said casing, a second ironing element positioned above said first named ironing element, an arm connected to said second named ironing element and extending horizontally rearward therefrom, said arm having its rear end turned downwardly, said down-turned portion having a forward projection, a supporting lever pivotally connected to said down-turned portion of said arm, another member pivotally connected to said forward extension of

- said arm, means for actuating said supporting lever to rock said arm about said last named member and thereby reciprocate said second named ironing element over the surface of said first named ironing element, and means for actuating said member to tilt said arm about said supporting lever and thereby move said second named ironing element toward and from said first named ironing element.
10. 7. The combination in an ironing machine, of a portable casing adapted to rest upon a table, an ironing element mounted on said casing, a second ironing element positioned above said first named ironing element, an operating arm connected to said second named element and extending rearwardly therefrom, a pair of supporting members each having a pivotal connection with said arm, means for actuating one of said supporting members to reciprocate said second named ironing element parallel to the surface of said first named ironing element, and means for actuating the other of said supporting members to move said second named ironing element toward and from said first named ironing element.
20. 8. The combination in an ironing machine, of a casing, an ironing element mounted on said casing, a second ironing element positioned above

said first named ironing element, an operating arm pivotally connected to said second named ironing element, an operating shaft in said casing, a pair of eccentrics mounted on said shaft, connections from one of said eccentrics to said arm for effecting a reciprocating motion of said second named ironing element over the surface of said first named ironing element, and means including connections from the other of said eccentrics to said arm for effecting relative separation of said ironing elements.

9. The combination in an ironing machine, of a pair of ironing plates having flat cooperating ironing surfaces, means including an eccentric for effecting relative movement of said plates toward and from each other, a driving motor, means including complementary clutch members for forming a driving connection between said eccentric and said motor, means tending normally to effect engagement of said clutch member, a manually operated member for controlling the disengagement of said clutch members, and independent means actuated by said motor for effecting a relative reciprocating motion of said ironing plates in parallel planes.

25.

HAROLD L. HART.
